SHIELD CAN WITH SPRING ATTACHMENT
MEANSEdward L. Johnson, South Orange, N. J., assignor
to The Palnut Company, Irvington, N. J., a
corporation of New Jersey

Application December 15, 1945, Serial No. 635,392

8 Claims. (Cl. 174—35)

1

This invention is particularly applicable to the attachment of an electrostatic shielding can to a chassis plate and hence it will be disclosed and discussed in that connection. Certain features of the invention are, however, applicable to other attachments.

Coils and other circuit elements employed in radio and other electrical apparatus are customarily mounted upon a metal chassis plate. Often these elements require shielding, usually electrostatic shielding. A common form of electrostatic shield is a metal "can" (usually aluminum) which is telescoped over the coil or other circuit element and secured to the chassis plate. Sometimes these "cans" are merely tubular bodies but ordinarily one end of the tube is closed and the other end is open, the open end or mouth being placed against or adjacent to the chassis plate. For quantity production and assembly of apparatus of this sort, some inexpensive means is necessary for quickly and reliably securing the shielding can to the chassis plate. Also, the securing means should be one which provides for ready removal of the can for replacement of, or servicing of, the circuit element enclosed within it. Various devices have been used or suggested for attaching shielding cans to chassis plates, but none of them known to me has had as great facility of assembly or as great reliability in use as is desirable. Also various of the attachment means used heretofore have been more expensive to manufacture than is desirable.

An object of the present invention is to provide an inexpensive shielding-can and chassis-plate assembly wherein the can can be secured to the chassis plate with great rapidity and with a high degree of reliability in the resulting attachment.

Another object of the invention is to provide an improved shielding-can and chassis-plate attachment requiring only a simple telescopic motion to effect the assembly.

A further object of the invention is to provide a fastening device for attaching a shielding can to a chassis plate, of such character that the attachment can be made by a simple telescoping movement and that thereafter the can will be held against the chassis plate by spring tension.

Additional objects of the invention are to provide a fastening device which can be rapidly and inexpensively manufactured from sheet metal, which attaches the parts of the assembly by simple telescopic movement, which provides for expeditious disassembly, and which requires neither tools nor any skilled operation to make the assembly and the disassembly.

My invention is clearly defined in the appended claims. Where parts are, for clarity and convenience, referred to on the basis of their oriented position shown in the accompanying

2

drawing, no limitation as to positioning of the entire structure is to be implied, since it will be understood that the entire structure may be inverted or that it may be used in any inclined position. Also in both the description and the claims, parts at times may be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Fig. 1 shows a shielding-can and chassis-plate assembly embodying the present invention, the can being shown in side elevation and the plate being shown in section.

Fig. 2 is a view similar to Fig. 1, the assembly being viewed at right angles to the direction of view of Fig. 1, and the view illustrating the manner in which the can is installed on the plate. This view shows the can in elevation and the plate in section, the line of section of the plate being midway between the right and left sides of the can as viewed in Fig. 1.

Fig. 3 is a horizontal section taken on the lines 3—3 of Fig. 1.

In Figs. 1, 2 and 3, a first form of the fastening device is shown.

Fig. 4 is a front elevation, on an enlarged scale, showing a second form of fastening device per se.

Fig. 5 is a side elevation of the second form of fastening device per se, drawn to the same scale as Fig. 4.

Fig. 6 is a detail view on a still larger scale, partly in elevation and partly in section, showing the latching of either the first or second forms of fastening device to the chassis plate.

Fig. 7 is a view similar to Fig. 6 showing a modification which may be incorporated in both the first and second forms of fastening device.

Fig. 8 is a detail sectional view showing a fastener-receiving hole in a chassis plate and a burr associated with the hole.

Fig. 9 is a detail sectional view showing a fastener-receiving hole in a chassis plate and fastener-interlocking indentations which may optionally be formed adjacent thereto.

A shielding can designated as a whole by 10 has a tubular body 11, and it may have a top 12. The can is adapted to enclose a coil or other circuit element indicated diagrammatically at 13 and which may be attached to either the chassis plate or the can. Ordinarily the bottom of the tubular body 11 is open, leaving a rim or annular edge that is adapted to rest directly against the upper face of a chassis plate 14. Fixedly secured to opposite sides of the can body 11 are

fastening devices 15, 15. These have end portions which project through rectangular holes 16, 16 in the chassis plate and latch beneath the plate, each hole 16 and the surrounding metal constituting a receptacle to receive the end portion of the fastening device.

Each fastening device 15 is a one-piece sheet metal stamping having a hub 17 provided with a hole analogous to hole 24 in Fig. 4. Extending upwardly and then laterally from the hub is an L-shaped finger 18. Extending downwardly from the hub are spaced legs 19 and 20 disposed in edge-to-edge relation. The end portion *b* of each leg is so formed as to provide a cam surface *c* and a latching lip *d*. The legs 19 and 20 are bowed laterally throughout a zone *Z*, the arc of the bowed portion being preferably substantially less than a semicircumference, as is shown in the drawing. The fastener is made of suitable springy metal, and I preferably stamp it from sheet metal. For most purposes I prefer to stamp it from spring steel and then harden and temper the stamping. Phosphor bronze, beryllium copper, spring brass, and other spring alloys may also be used.

The fastener 15 may be fixedly secured to the can 10 by a rivet 25 which passes through a hole therein and a suitably located hole in the side wall of the can. The can is provided with a suitable formation, e. g., a hole 26, which finger 18 engages to prevent the fastener from swinging pivotally on rivet 26. The can-adjacent surface of the hub 17 lies directly against the can and establishes the attachment plane of the fastener.

Prior to assembly of the can with the plate, the circuit element 13 is mounted either on the plate or in the can. Then the can is put in place, the ends of the fasteners 15, 15 being inserted into the rectangular holes 16, 16, the spacing of which is equal to the spacing between the end portions of the two fastening elements 15, 15 which are attached to the can. The long dimension of each hole 16 is such that as the end of the fastener enters the hole, the short edges of the hole are engaged by the cam surfaces *c*, *c*, thereby forcing legs 19 and 20 toward one another. The proportion of parts is such that without distortion of the bowed portion *Z* of legs 19 and 20, the lips *d*, *d* will not pass beneath the chassis plate. However, by exerting inward pressure on the bowed portions of the two fasteners with the thumb and forefinger, as indicated in Fig. 2, the bowed portions will be flexed, resulting in elongation of the fasteners and such extension of the ends of the fasteners that the lips *d*, *d* will pass beneath the chassis plate. Thereupon the legs 19 and 20 will spread due to their resiliency, and the fastener will latch to the chassis plate as shown in Figs. 1 and 6. In such latched condition the bowed legs 19 and 20 are maintained under stress and hold the end of the can against the chassis plate by spring tension. This is of great advantage, not only to prevent looseness and rattling of the can, but also to establish and maintain low resistance electrical connection of the can to the chassis plate.

To remove the can 10, the end portions *b*, *b* of each fastener are manually pressed toward one another, whereupon the springy bowed portion of each fastener retracts the lips *d*, *d* into hole 16, and the can may then be lifted from the chassis plate.

The lips *d*, *d* may be so disposed that when latched to the chassis plate these lips lie in the

plane of the underside of the chassis plate. This is shown in Fig. 6. It is not desirable that these lips extend outwardly and downwardly from the legs, as the lips would then tend to cam out of holes 16, 16 under the spring action of the bowed portion *Z* of the fasteners. I prefer that the lips *d*, *d* be so disposed as to nominally extend outwardly and somewhat upwardly from the legs, so that under the variations incident to quantity production there will be no danger of the lips of any particular fastener extending outwardly and downwardly.

Fig. 7 shows fastener legs 19a and 20a provided with latching lips *d*', *d*'' extending outwardly-upwardly to such an extent as to give definite prongs *p*, *p* which will embed somewhat in the metal of the plate 14, particularly if it be of aluminum or other soft metal. When so embedded these prongs oppose any accidental or fortuitous movement of the legs 19a and 20a toward unlatching position. Also, the chassis plate may be a plate 14a (Fig. 9) provided with a rectangular hole 16a adjacent to which are preformed indentations such as *e*, *e* to receive the tips of outwardly-upwardly inclined latching lips. Alternatively, the chassis plate may be a plate 14b (Fig. 8) having a fastener-receiving hole 16b so stamped as to leave a burr 31 on the underside which will oppose accidental unlatching of the fastener by forming a barrier to accidental unlatching movement of the tips of outwardly-upwardly inclined latching lips.

It will be seen that by means of two fasteners 15, 15 a shielding can may be quickly and securely installed on a chassis plate. Any force tending to shift the can laterally on the plate, as viewed in Fig. 2, is promptly opposed by the bottom portion of the can laterally engaging one of the fasteners 15 which is held against lateral movement by its telescopic arrangement with plate hole 16. If the can be shifted laterally as viewed in Fig. 1, it may tend to shift the end of either fastener leg 19 or fastener leg 20 to a position of lesser latching engagement with the plate, but the other leg of the fastener either cannot move or is pushed further into latching relation with the plate. For some classes of service, interfitting or interlocking formations are provided between the can and the plate to oppose lateral and rotative forces tending to shift the can on the surface of the plate. Fig. 3 shows the plate 14 provided with a plurality of upstruck tabs 28 that are arranged in a series which is embraced by the open end of the can. These tabs and the open end portion of the can constitute interfitting formations effective to oppose rotative and lateral movement of the can on the surface of the plate. It will be understood, however, that for many classes of service these tabs 28 may be omitted, no interfitting between the can per se and the plate being needed.

Fig. 2 shows the open end or mouth of the can provided with a projecting tongue 29, one or more of which may be provided on opposite sides of the can to interlock with appropriately located additional holes such as 30 in the chassis plate to oppose rotative and lateral movement of the can on the surface of the plate. Only a single tongue 29 is shown in Fig. 2 and it is located at the back side of the can as viewed in Fig. 2. Since the line of section of plate 14 in Fig. 2 is midway between the front and back sides of the can as viewed in that figure, the tongue 29 and the hole 30 appear only in dotted lines. It will be understood that tongues 29 may be either in

addition to, or in lieu of tabs 28, and that for many classes of service both may be omitted.

The can 12, instead of being equipped with the first form of fastener shown in Figs. 1, 2 and 3, may be equipped with fasteners of the second form which is shown in Figs. 4 and 5. When so equipped, the can may be latched to and unlatched from the chassis plate in the same manner. However, the form of fastener shown in Figs. 4 and 5 affords a more positive and secure attachment of the can to the chassis plate as will presently appear.

The second form of fastener, designated as a whole by 15', differs from the first form of fastener primarily in its different proportioning and in the addition of a bridge member connecting the two legs of the fastener. Fastener 15' includes a hub 17', an L-shaped finger 18', a bowed portion Z', end portions b', b', cam surfaces c', c' and latching lips d', d'; all of these parts corresponding to the parts of fastener 15 which are designated by reference characters which correspond respectively but which do not have a prime mark. When a can such as 12 is to be equipped with the second form of fastener, it will, of course, be provided with suitably located attachment holes positioned to register with hole 24 and finger 18'.

The legs 19' and 20' are connected by an integral bridge 40 which is preferably located near the middle of the legs. When the ends b', b' of the legs are cammed towards one another, the bridge 40 flexes, the flexure disappearing as the ends b', b' move into latched relation with the chassis plate. The bridge stiffens the fastener in respect to the edgewise movement of the free ends of the legs toward and away from one another in latching and unlatching, without however stiffening the legs in respect to the thumb and finger pressure required to distort the bowed portion Z' in making an assembly as indicated in Fig. 2.

The end portions of the legs of fastener 15' may be formed either as shown in Fig. 6 or Fig. 7. If formed as shown in Fig. 6 the latching lips will lie in the plane of the underside of the chassis plate. If formed as in Fig. 7 the latching lips will incline outwardly-upwardly from the legs giving the definite barb-like prongs, p, p shown in Fig. 7. The second form of fastener 15' may, of course, be used with the chassis plate 14a of Fig. 9 or with the chassis plate 14b of Fig. 8, both of which have already been described.

Bridge 40 is preferably located far enough from hub 17' to provide an opening 41 which is long enough to permit another fastener to drop readily through the opening. This prevents one fastener from becoming latched to another when a number of fasteners are bulked together for handling or shipping. In some instances the two legs of the fastener may be connected by two integral bridges which are spaced apart lengthwise of the fastener legs. In such case the opening between the hub and the nearest bridge, and the opening between the two bridges, may be made so small that it is impossible for the end of another fastener to latch into these openings.

I claim:

1. In a shield-can and chassis-plate organization, a shield can, a chassis plate, a pair of elongated fasteners attached to opposite sides of the can, the fasteners extending beyond the mouth of the can and being provided with terminal latching formations to project through holes in the chassis plate and latch thereto, said terminal

formations being initially too close to the mouth of the can to latch to the plate, and the fasteners having springy portions which are bowed outwardly from the sides of the can, said outwardly bowed portions being deformable toward the can by thumb and finger pressure to thereby extend the terminal formations to a sufficient distance from the mouth of the can to latch to the plate, and said outwardly bowed portions, upon completion of the assembly, exerting spring pressures which biases the mouth of the can against the plate.

2. In a shield-can and chassis-plate organization, a shield can, a chassis plate, a pair of elongated fasteners of springy sheet metal attached to opposite sides of the can, the fasteners extending beyond the mouth of the can and being provided with terminal latching formations to project through holes in the chassis plate and latch thereto, said terminal formations being initially too close to the mouth of can to latch to the plate, and the fasteners having springy portions which are bowed outwardly from the sides of the can, said outwardly bowed portions being deformable toward the can by thumb and finger pressure to thereby extend the terminal formations to a sufficient distance from the mouth of the can to latch to the plate, and said outwardly bowed portions, upon completion of the assembly, exerting spring pressure which biases the mouth of the can against the plate.

3. A springy snap-in fastener of stamped sheet metal comprising a hub and a pair of spaced legs extending therefrom in edge-to-edge relationship, the hub and the end portions of the legs lying in the plane of the sheet and the major intervening portions of the legs being bowed transversely of the plane of the sheet and rendering the legs yieldingly extensible by lateral pressure applied to the bowed portions, the hub being pierced for riveting to a member that is to be fastened, the end portion of each leg being provided with a cam surface for camming the leg toward the other leg when the ends of the legs are inserted into a suitable hole in a plate-like support, and the end portion of each leg being also provided with an outwardly extending lip for latching with the plate-like support.

4. A springy snap-in fastener of stamped sheet metal comprising a hub and a pair of spaced legs extending therefrom in edge-to-edge relationship, the hub and the end portions of the legs lying in the plane of the sheet and the major intervening portions of the legs being bowed transversely of the plane of the sheet and rendering the legs yieldingly extensible by lateral pressure applied to the bowed portions, the hub being pierced for riveting to a member that is to be fastened and being provided with a projecting finger to interlock with the member and prevent rotation of the fastener on the rivet, the end portion of each leg being provided with a cam surface for camming the leg toward the other leg when the ends of the legs are inserted into a suitable hole in a plate-like support, and the end portion of each leg being also provided with an outwardly extending lip for latching with the plate-like support.

5. A fastener composed of a single piece of stamped spring sheet steel, hardened and tempered, said fastener comprising: a pierced hub for attachment by a rivet to a member to be fastened, the hub establishing an attachment plane at which the fastener engages the member 75 to be fastened, a finger adjacent the hub and

7
projecting inwardly from the attachment plane for engagement with a formation in the member to hold the fastener against rotation about the rivet, a pair of elongated spaced legs extending from the hub in edge-to-edge relationship, latching formations on the ends of the legs for telescopic latching with a complementary member, and a fixedly-positioned bridge connecting the legs at a location remote from both ends of both legs, a longitudinal zone of each leg being formed as a spring portion bowed outwardly of the attachment plane, the bowed spring portion being deformable by finger pressure to lengthen the leg and being operative when released to resiliently retract the end of the leg.

6. A fastener composed of a single piece of stamped spring sheet steel, hardened and tempered, said fastener comprising: a hub portion for attachment to a member to be fastened, the hub establishing an attachment plane at which the fastener engages the member to be fastened, a pair of elongated spaced legs extending from the hub in edge-to-edge relationship, latching formations on the ends of the legs for telescopic latching with a complementary member, and a fixedly-positioned bridge connecting the legs at a location remote from both ends of both legs, a longitudinal zone of each leg being formed as a spring portion bowed outwardly of the attachment plane, the bowed spring portion being deformable by finger pressure to lengthen the leg and being operative when released to resiliently retract the end of the leg.

7. A fastener composed of a single piece of spring metal, said fastener comprising: a hub portion for attachment to a member to be fastened, the hub establishing an attachment plane at which the fastener engages the member to be fastened, a pair of elongated spaced legs extending from the hub in side-by-side relationship, latching formations on the ends of the legs for telescopic latching with a complementary member, and a fixedly-positioned bridge connecting the legs at a location remote from both ends of both legs, a longitudinal zone of each leg being

5 formed as a spring portion bowed outwardly of the attachment plane, the bowed spring portion being deformable by finger pressure to lengthen the leg and being operative when released to resiliently retract the end of the leg.

10 8. A fastener composed of a single piece of stamped sheet steel, hardened and tempered, said fastener comprising: a pierced hub for attachment by a rivet to a member to be fastened, the hub establishing an attachment plane at which the fastener engages the member to be fastened, means connected with the hub and projecting inwardly from the attachment plane for engagement with the member to hold the 15 fastener against rotation about the rivet, a pair of elongated spaced legs extending from the hub in edge-to-edge relationship, latching formations on the ends of the legs for telescopic latching with a complementary member, and a fixedly-positioned bridge connecting the legs at a location remote from both ends of both legs, a longitudinal zone of each leg being formed as a spring portion bowed outwardly of the attachment plane, the bowed spring portion being deformable by finger pressure to lengthen the leg and being operative when released to resiliently retract the end of the leg.
